GARMENT

Max Kops, Jr., New York, N.Y., assignor to Kops Brothers, Inc., New York, N.Y., a corporation of New York

Filed Aug. 7, 1963, Ser. No. 300,522
4 Claims. (Cl. 128—546)

The present invention relates to a garment and more particularly to a garment having exceptional abdominal control.

A basic and perhaps most important function of the girdle, corselette, and the like, is to ensure dependable abdominal control. Such control must be achieved unobtrusively and without sacrificing the comfort of the garment. Further, such control should be expected to last throughout the life of the entire garment.

It is, therefore, an object of the present invention to provide a garment which will meet the foregoing requirements.

It is another object of the present invention to provide an abdominal panel which may be incorporated into various garment designs.

Additional objects and advantages of the present invention will become apparent from the following description and drawing, in which:

FIG. 1 is a front view of a garment of the present invention;

FIG. 2 is a back view of the garment of FIG. 1; and

FIG. 3 is a fragmentary view of another embodiment of the present invention.

Referring now to the drawing in FIGS. 1 and 2 the present invention is shown applied to a regular, or open, girdle. An abdominal panel 10 extends from the waistline 12 to the crotch 14 of the girdle. The abdominal panel 10 widens out at its central portion. A side panel 16 is connected along its inner edge 18 at each side of the abdominal panel 10. At the rear of the garment, a back panel 20 connects the two side panels 16. The back panel may have a separate top section 21 if desired.

The abdominal panel 10 is divided into two substantially identical half-sections 22 which meet along a generally vertical centerline 24. Each half-section 22 has a plurality of diagonal tucks 26 which meet the diagonal tucks 26 of the other half-section in a V-shape. Preferably the abdominal panel 10 has two layers, an outer layer 28 and an inner layer 30. While the top half-sections have diagonal tucks 26 which meet in a V-shape, the inner half-sections have a second plurality of diagonal tucks 32 which meet in an inverted V-shape. As shown in the drawing, the apices of each pair of V's meet together to form contiguous diamond shapes extending over the vertical centerline 24.

The side panels 16 and the back panel 20 may be made of two-way or one-way stretch materials as shown. The abdominal panel 10 however, is made of a firm non-stretch material in which the particular diagonal tucking described provides exceptional abdominal control. Indeed, the abdominal panel may be beneficially incorporated in a diversity of girdle designs to improve their abdominal control.

It has been found that a superior construction is obtained when the abdominal panel is used in conjunction with side panels which have a double-layer portion 34 of the stretch material of which the side panel is composed. The double-layer portion 34 is of generally triangular shape with its base 36 extending over approximately two-thirds of the central portion of the side panel at its inner edge 18. The side edges 38 of the triangle extend diagonally toward each other to terminate at the sides of the garment. It will be noted that the base 36 of the triangle extends from the uppermost outer tuck

2

26 to the lowermost inner tuck 32 in order to increase the pressure in the abdominal area.

The present invention is also illustrated in FIG. 3 where it is shown as a panty girdle. Here, too the abdominal panel 40, substantially as described in the previous embodiment, extends from the waistline 42 to the crotch 44 and widens out at its central portion. The same firm, dependable control is obtained with this panty girdle as with the regular girdle of FIGS. 1 and 2.

It has thus been shown that the present invention provides a garment, such as a girdle or the like, having extra support and control over the abdominal area. The construction utilizes a nonstretch material and shapes it permanently by a series of purposefully designed, stitched tucks for a control which will last throughout the life of the garment.

While specific embodiments of the invention have been shown and described in detail to illustrate the application of the invention, it will be understood that the invention may be embodied otherwise without departing from such principles.

What is claimed is:

1. A garment having an abdominal panel with an outer layer and an inner layer of material, each of the outer layer and the inner layer of said abdominal panel having two substantially identical half-sections meeting along a generally vertical centerline, each half-section of the outer layer having a plurality of the diagonal tucks, said tucks meeting in each half-section of the outer layer in a V-shape, each half-section of the inner layer having a second plurality of diagonal tucks, said tucks meeting in each half-section of the inner layer in an inverted V-shape, the tucks of each layer being similarly spaced and angled and arranged so that the apices of the tucks in the outer layer and the apices of the tucks in the inner layer meet together to form contiguous diamond shapes.

2. A garment having an abdominal panel with an outer layer and an inner layer of nonstretch material extending from approximately the waistline to the crotch, each of the outer layer and the inner layer of said abdominal panel being divided into two substantially identical half-sections meeting along a generally vertical centerline, each half-section of the outer layer having a plurality of diagonal tucks, said tucks meeting in each half-section of the outer layer in a V-shape, each half-section of the inner layer having a second plurality of diagonal tucks, said tucks meeting in each half-section of the inner layer in an inverted V-shape, the tucks of each layer being similarly spaced and angled and arranged so that the apices of the tucks in the outer layer and the apices of the tucks in the inner layer meet together to form contiguous diamond shapes.

3. A garment having an abdominal panel with an outer layer and an inner layer of nonstretch material extending from approximately the waistline to the crotch and a side panel connected along its inner edge at each side of said abdominal panel, each of said side panels being made of a stretch material and having a double-layer portion of generally triangular shape, said triangle having a base which extends over approximately two-thirds of the central portion of the side panel at its inner edge and side edges which extend diagonally toward each other to terminate at the sides of the garment, each of the outer layer and the inner layer of said abdominal panel being divided into two substantially identical half-sections meeting along a generally vertical centerline, each half-section of the outer layer having a plurality of diagonal tucks, said tucks meeting in each half-section of the outer layer in a V-shape, each half-section of the inner layer having a second plurality of diagonal tucks, said tucks meeting in each half-section of the inner layer in an inverted V-shape, the tucks of each layer being similarly spaced

and angled and arranged so that the apices of the tucks in the outer layer and the apices of the tucks in the inner layer meet together to form contiguous diamond shapes.

4. A garment having an abdominal panel with an outer layer and an inner layer of nonstretch material extending from approximately the waistline to the crotch, each of the outer layer and the inner layer of said abdominal panel being divided into two substantially identical half-sections meeting along a generally vertical centerline, each half-section of the outer layer having a plurality of diagonal tucks, having an uppermost and a lowermost tuck, said tucks meeting in each half-section of the outer layer in a V-shape, each half-section of the inner layer having a second plurality of diagonal tucks, said tucks meeting in each half-section of the inner layer in an inverted V-shape, the tucks of each layer being similarly spaced and angled and arranged so that the apices of the tucks in the outer layer and the apices of the tucks in the inner layer meet together to form contiguous diamond shapes, and a side panel connected along its inner edge at each side of said abdominal panel, each of said side

panels being made of a stretch material and having a double-layer portion of generally triangular shape, said triangle having a base positioned along the line of connection to the abdominal panel and which extends from the uppermost tuck to the lowermost tuck over approximately two-thirds of the central portion of the side panel at its inner edge and side edges which extend away from the abdominal panel and diagonally toward each other to terminate at the sides of the garment.
